PARTITIONED CARTON

Emil M. Schaefer, Minneapolis, Minn.

Application June 11, 1956, Serial No. 590,508

8 Claims. (Cl. 229—28)

This invention relates to an improvement in partitioned carton and deals particularly with a tray shaped body having integral partitions for separating the goods enclosed.

Various types of goods have long been packaged in trays having a partitioned structure therein for separating the goods contained. For example, in certain bakery products, it is desirable to keep the various units from contact one with the other and it is common practice to enclose such goods in a carton comprising a paper board tray having an integral partitioned unit or filler therein. Goods packaged in trays of this type are often overwrapped in a wrapping of transparent material such as cellophane for the proper display of the goods packaged. As the partitioned units are usually separately formed, it is necessary for the person packaging the goods to first open up the tray into proper form and then insert the partition member or filler into the tray, the filler acting to hold the tray in proper condition. Thus before the goods can be packed, not only does the tray have to be opened from its flat form but also the filler has to be expanded so that the partition forming elements are at proper angular relation. Even in cases where the partition units are placed into trays which are automatically formed with corner locks, it is necessary for the operator to at least expand the partition units into form and insert these units into the tray before the contents may be inserted.

It is an object of the present invention to produce a tray-like body having a series of partitions which are formed integrally with the body of the tray. The body of the tray is normally of the infolded type so that the walls of the tray may be quickly folded into erect condition. The construction is so arranged, that a portion of the partition forming element may be simultaneously erected and the entire tray may be formed from a single blank of paperboard.

A feature of the present invention resides in the fact that the fillers are attached to the tray in the set up condition of the structure. As a result, all of the various partitions remain properly in place and it is not possible for the various partition forming elements or fillers to be accidentally withdrawn from the trays during the packaging thereof or after the packages have been opened for use. Accordingly it is possible for the consumer to remove a part of the contents of the tray without danger of disturbing the filler or accidentally removing it so that the remaining goods will come into contact.

A further feature of the present invention resides in the provision of a display member comprising a tray shaped body having three connected sides and a fourth open side. The tray is provided with a bottom but is open at the top. As a result, when the goods are overwrapped, they are more effectively displayed than if the tray were possessed of four sides. At the same time, the construction is such that the partition forming element will not move out of place even though the tray is provided with an open side.

2

These and other objects and novel features of the present invention will be more clearly and fully set forth in the following specification and claims.

In the drawings forming a part of the specification:

5 Figure 1 is a plan view of the blank from which the carton is formed.

Figure 2 is a cross-sectional view through the formed tray, the position of the section being indicated by the line 2—2 of Figure 1 of the drawings.

10 Figure 3 is a sectional view on the line 3—3 of Figure 1 of the drawings.

Figure 4 is a front elevational view of the carton in set up form.

15 Figure 5 is a diagrammatic view of the blank from which the carton is formed.

Figure 6 is a plan view of the blank after it is partially folded.

Figure 7 illustrates the blank in a later stage of completion.

20 Figure 8 is a plan view of the completely formed flat blank.

The carton A is formed as is best illustrated in Figure 1 of the drawings, and is formed from the blank illustrated in Figure 5. While the details of construction may be varied to some extent, the carton A is shown as having a bottom panel 10 which is foldably connected along opposite ends by parallel fold lines 11 and 12 to end walls 13 and 14 respectively. A fold line 15 extends across a third edge of the bottom panel 10, this fold line 15 foldably connecting the bottom to the rear wall 16. Flaps 17 and 19 foldably connected to the rear edges of the end walls 13 and 14 along fold lines 20 and 21, which fold lines are preferably aligned with the fold line 15.

35 In order that the tray may be infolded and adhered in flat form, a diagonally extending fold line 22 extends across the end wall 13 from the juncture of the fold lines 11 and 15, forming a triangular rear section 23 of the end wall 13 which may be folded into surface contact with the adjoining portion of the end wall 13. A similar diagonal fold line 24 extends across the end wall 14, emanating from the juncture of the fold lines 12 and 15. The fold line 24 permits the infolding or outfolding of the triangular corner portion 25 onto an adjoining portion of the end wall 14 during the gluing operation.

40 As the carton of the present construction is shown divided into six compartments of substantially equal volume, a panel 26 is foldably connected to the central portion of the bottom panel 10 along a fold line 27. This panel 26 is of a width equal to substantially one-third the width of the bottom panel 10 and the fold line 27 extends along the middle one-third of the panel edge 29. The panel 26 is also substantially equal to approximately one-half of the width of the panel 10 between the edge 29 and the fold line 15. This panel 26 is designed to be folded into surface contact with the panel 10 in a manner which will be later described in detail.

45 A central partition forming panel 30 is foldably connected to the panel 26 along a fold line 31 which is parallel to the fold line 27. This partition panel 30 preferably extends substantially the full length of the panel 10 between the fold lines 11 and 12. The partition panel 30 is foldably connected along a fold line 32 to a similar central partition panel 33. As will be later described, the panel 33 is also substantially the full length of the bottom panel 10 and is equal in height to the panel 30. If the various partitions are to extend the full height of the tray, as is usual in constructions of this type, the height of the panels 30 and 33 is equal to the height of the end walls 13 and 14.

50 The panel 33 is foldably connected along a fold line 34 to an anchoring panel 35 which is substantially sim-

ilar in shape and size to the panel 26. In other words, the panel 35 is preferably one-third of the length of the bottom panel 10 and is of a width equal to substantially half the distance between the edge 29 of the bottom panel and the parallel fold line 15 thereof. The fold line 34 normally extends along the middle one-third of the bottom panel for a purpose which will be later described more in detail.

A pair of right angularly extending partition panels 36 and 37 are hingedly connected to opposite ends of the panel 26 along parallel fold lines 39 and 40. Integral with the ends of these partition panels 36 and 37 and cut from the body of the partition panel 30 are provided tongues 41 and 42 having arcuate edges 43 and 44. The tongues 41 and 42 are usually of a height equal to approximately one-half of the height of the partition panels 36 and 37 when they are folded upwardly in right angular relation to the panel 26. The purpose of these tongues will also be later described more in detail.

A pair of partition panels 45 and 46 are pivotally or hingedly connected to the anchoring panel 35 along parallel fold lines 47 and 49 which usually intersect the fold line 34 at substantially right angles. The fold lines 47 and 49 are preferably aligned with the previously described fold lines 39 and 40. Furthermore the partition panels 45 and 46 are usually the same height as the partition panels 36 and 37. The ends of the partition panels 36 and 37 adjoining the tongues 41 and 42 are preferably notched out as is indicated at 50 and 51 and the ends of the partition panels 45 and 46 which are most closely adjacent to the partition panel 33 are also notched out as indicated at 52 and 53 respectively. The purpose of these notches is to simplify the erection of the various partition panels and the notches may be eliminated if desired or modified in size.

Notches 54 and 55 are also provided in the partition panel 33, these notches being just outwardly of the ends of the fold line 34. The notches 54 are provided with arcuate ends 56 and 57 which communicate with cut lines 59 and 60 which extend parallel to the fold line 32. The notches are also cut along cut lines 61 and 62 which are aligned with the fold lines 47 and 49. As a result, the notches 54 and 55 are shaped to somewhat coincide with the notches formed in the partition panel 30 by the removal of the tongues 41 and 42. However, the cut lines 59 and 60 form a single thickness of material extending into the notches, as is best illustrated in Figure 4 of the drawings.

In the formation of the tray, adhesive is locally applied to the partition panel 30 or the partition panel 33. Accordingly, when the two partitions 30 and 33 are folded into surface contact, these two panels will adhere together to form a central partition unit extending from end to end of the tray midway between the front and the rear edges thereof as is best illustrated in Figures 1 through 4 of the drawings.

During the folding operation of the two panels 30 and 33, the blank is also folded along the fold line 34 so that the panel 35 and the adjoining partition panels 45 and 46 are in surface contact with the partition panel 33 to which they are hinged along the hinged line 34. The entire structure is ordinarily simultaneously folded along the fold line 27 so that the entire added portion of the blank above the fold line 27 overlies the bottom panel 10. The anchoring panel 35 is provided with adhesive to adhere this anchoring panel to the base panel 10 and if desired, the panel 26 may also be adhered to the surface of the base panel 10, although this is not necessary.

The carton A is now in the position illustrated in Figure 6 of the drawings. It will be noted that areas of adhesive 65 and 66 are provided on the partition panels 45 and 46 or upon the undersurfaces of the tongues 41 and 42. From Figure 6 of the drawings, it will be shown that the tongues 41 and 42 underlie the partition panels 45 and 46 when the carton is thus folded and

are adhered thereto. As a result of this arrangement, the partition panels 36 and 45 are connected in substantially the same plane by the tongue 41 and the partition panels 37 and 46 are similarly connected in substantially the same plane by the tongue 42.

The tray is then completed by an infolding or an out-folding operation. In the drawings, the tray is shown infolded with the end panels 13 and 14 folded to overlie the ends of the partition structure and to overlie the ends of the base panel 10 as illustrated in Figure 7 of the drawings. The end walls 13 and 14 are simultaneously folded along the diagonal fold lines 22 and 24 so that the triangular areas 23 and 25 overlie portions of the end walls 13 and 14. The flaps 17 and 19 are simultaneously folded in the opposite direction so as to overlie the triangular areas 23 and 24. Adhesive is applied to the flaps 17 and 19, as is best illustrated in Figure 7 of the drawings.

The tray is then completed by folding the rear wall 16 so that the ends thereof overlie the end tabs 17 and 19 and are adhered thereto. The carton is then completed in its flat form.

When the carton is completed it appears as indicated in Figure 8 of the drawings. It is shipped and stored in this flat state. When it is desired to use the carton, the walls of the tray are swung into vertical position by merely grasping the inner or upper edges of the end walls 13 and 14 and pulling these walls upwardly along their respective fold lines 11 and 12. This automatically erects the rear wall 16 into vertical form.

The combined center partition panels 30 and 33 are next swung into erect form between the end walls 13 and 14, the ends of the partition panel holding the end walls 13 and 14 from collapsing inwardly. The fingers are next inserted between the right angularly extending partition panels and these combined panels also folded upwardly into right angular relation with the base panel 10. As the right angularly extending partition panel connected by the tongues 41 and 42, these partition units may be easily folded upwardly into vertical position.

During the initial folding of the partition panels 36, 46 and 37, 46, the folding action is unrestricted because of the arcuate cut lines 56 and 57 which correspond with the similar cut lines in the partition panel 30. However, when the combined right angularly extending partition panels assume an angle of about 45° from the bottom panel, the upper edges of the tongues 41 and 42 engage the single thickness portion of the panel 33 which projects downwardly into the notches in the manner best illustrated in Figure 4 of the drawings. These single thickness portions are indicated by the numerals 67 and 69 in this figure. These projecting portions tend to cut into the upper surfaces of the tongues 41 and 42 creating a wedging action which tends to hold the right angularly extending partition panels in an upright position. If desired, the tongues 41 and 42 may be slit or notched as indicated at 70 and 71 in Figure 5 of the drawings, the slits 70 and 71 serving mainly to accommodate the single thickness portions 67 and 69 and limiting the tendency for the tongues to tear. In other words, by initially slitting the tongues, the task of erecting the right angularly extending partition members is simplified without deleterious effects upon the strength of the tongues.

In accordance with the patent statutes, I have described the principles of construction and operation of my partitioned carton, and while I have endeavored to set forth the best embodiment thereof, I desire to have it understood that obvious changes may be made within the scope of the following claims without departing from the spirit of my invention.

I claim:

1. A collapsible compartment member foldable into or out of flattened form including a base having a series of panels secured to an edge thereof, said panels including, in sequence, a connecting panel, a first partition

panel, a second partition panel, and an anchoring panel, said anchoring panel being secured in surface contact and said connecting panel and said anchoring panel being in substantial surface contact with said base, said connecting panel and anchoring panel being relatively narrow as compared to said partition panels and said base and located intermediate the ends thereof, substantially aligned notches in said partition panels in the edges thereof connected to said connecting panel and anchoring panel respectively, said notches being located outwardly of the sides of said connecting and anchoring panels, partition forming flaps hingedly connected to the side edges of said connecting and anchoring panels, and means extending through said notches connecting the partition forming flaps of said connecting panel with the partition forming panels of said anchoring panel in surface contact.

2. The structure described in claim 1 and including slits in said means extending through said notches into which a portion of one of said partition panels adjoining said notches may extend.

3. The structure of claim 1 and in which said means extending through said notches comprises projections on two of said partition forming flaps adhered in surface contact with portions of the remaining two partition forming flaps.

4. The structure of claim 1 and in which said notches are in the under portion of said partition panels when these partition panels are in upstanding relation, and these notches being of sufficient size to provide spaces through which said means connecting said partition forming flaps may fold from a position flat against said base to upright position intersecting said partition panels.

5. A flat glued erectable and collapsible compartment forming member including a bottom panel, a connecting panel foldably connected to one edge of said bottom panel and overlying a portion of said bottom panel, a first partition forming panel foldably secured to said connecting panel, a second partition forming panel foldably secured to said first partition forming member and adhered in surface contact therewith, an anchoring panel foldably connected to said second partition forming panel and overlying a portion of said bottom panel, the lines of fold connecting said panels being parallel, said partition panels being longer than said connecting panel and anchoring panel in a direction parallel the lines of fold and said partition forming panels being folded down parallel to said bottom panel, partition forming flaps foldably connected to the edges of said connecting panel and anchoring panel along parallel lines at right angles to the previously described lines of fold, the lines of fold connecting each partition forming flap to said connecting panel being substantially aligned with the lines of fold connecting said partition forming flaps to said anchoring panel, said partition forming flaps overlying portions of said bottom panel on opposite sides of said connecting panel and anchoring panel, two of said partition forming flaps including projections extending beyond the line of fold connecting the panel to which these flaps are connected to the adjoining partition forming panel, said projections being cut from said adjoining partition

forming panel and extending in overlapping adhered relation to the partition forming flaps on the opposite side of the lines of fold connecting said partition forming panels to said anchoring panel and said connecting panel, 5 said adjoining partition forming panel being notched at the areas from which said projections have been cut and the other partition forming panel being notched in at least partially corresponding areas, said notches being of proper size to permit said projections connecting said 10 partition forming flaps to fold into vertical position on said bottom panel when said partition forming panels are folded into vertical position.

6. The structure of claim 5 and including side walls hinged to the remaining three sides of said bottom panel, 15 said bottom panel being rectangular, corner flaps on certain of said side walls and overlapping portions of the adjoining side walls, and adhered thereto, said side walls overlying said bottom panel and substantially parallel thereto.

7. The structure of claim 5 and including slits in said projections into which a portion of one said partition forming panel may engage when in vertical position.

8. A compartment carton including a tray having a generally rectangular base panel, wall panels extending 20 upwardly along three sides thereof, a connecting panel foldably connected to the fourth side of said base panel and extending in superimposed relation to said base panel, a first partition panel foldably connected to said connecting panel along a fold line parallel to said fourth side, a second partition panel foldably connected to said first partition panel and secured in contiguous relation thereto, an anchoring panel foldably connected to said second partition panel along a fold line parallel to said fourth side, and partition forming wings foldably 25 connected to said connecting panel and said anchoring panel along parallel fold lines spaced from the ends of said partition panels and at substantially right angles to said fourth side, and projections on said partition forming wings on said connecting panel adhered in surface contact to portions of said partition forming wings on said anchoring panel, said partition forming panels having notches at the juncture between said partition forming panels and said connecting panel and said anchoring panel, said projections of said partition forming wings being foldable in said notches from parallel 30 relation to said connecting panel and anchoring panel to right angular relation thereto.
